DIELECTRIC HEATING DEVICE FOR THE EDGE GLUING

Werner Rueggeberg, Lancaster, Pa., assignor to Armstrong Cork Company, Lancaster, Pa., a corporation of Pennsylvania

Application April 17, 1952, Serial No. 282,750

5 Claims. (Cl. 219—10.45)

This invention relates to a dielectric heating device for edge gluing and is concerned particularly with a device for edge gluing pieces of cork composition, for instance, in the manufacture of gaskets. Gaskets are generally formed by dieing a single piece from a sheet of cork composition. This leaves a center portion of scrap which in a crankcase gasket, for example, may be of greater volume than the actual gasket. Frames of cork composition of the general outline of the gasket to be formed have been made of glued-up blocks, and these frames have been sliced into gasket blanks from which the gaskets have been die cut.

With the apparatus of the present invention, gasket segments may be severed from sheets of the desired thickness without substantial scrap loss and the segments adhesively joined together to produce a final gasket of the desired shape and thickness without further fabrication.

It is an object of this invention to provide an edge-gluing device in which an electrode may be reciprocated from an inoperative position to an operative position, embracing a workpiece and in which such motion may be utilized to closely couple the movable electrode to a high-frequency source.

Another object of the invention is to provide an edge-gluing device which will simultaneously form a plurality of heat-activated adhesive joints, such as in the joining of two side pieces to an end segment in the formation of a gasket, with the activation being effected by dielectric heating, employing spaced pairs of electrodes constituting part of a symmetrical high-frequency system.

A further object of the invention is to provide a dielectric heating device for edge gluing in which a separate capacitive current return path to the oscillator is provided, thus affording a reliable high-frequency switching system free of mechanical contacts.

An additional object of this invention is to provide a dielectric heating device in which one of an electrode pair is capacitively coupled to the high-frequency source, with the impedance of the coupling being substantially less than the impedance of the load to assure development of nearly all available generator voltage in the workpiece under treatment.

Other objects of the invention will be apparent from consideration of a typical embodiment of the invention which will be described in conjunction with the accompanying drawing, in which:

Figure 1 is a front elevational view of a gasket segment joining device embodying the invention;

Figure 2 is a side elevational view of the device of Figure 1;

Figures 3 and 4 are detailed perspective views to a larger scale than Figures 1 and 2, illustrating the electrode assemblies in separated position in Figure 3 and in closed position in Figure 4;

Figure 5 is a vertical sectional view to an enlarged scale of an upper electrode assembly;

Figure 6 is a view similar to Figure 5 of a lower electrode assembly; and

Figure 7 is a view similar to Figures 5 and 6 showing upper and lower electrode assemblies and an air switch constituting part of the capacitive current return path to the oscillator referred to previously.

5 While a gasket-segmenting device has been chosen for illustration of the invention, it will be understood that the device will be useful in edge gluing generally.

The general arrangement

10 The general arrangement shown in Figure 1 includes a pair of upper electrode assemblies 2 and 3, a pair of lower electrode assemblies 4 and 5, a source of high-frequency power 6 connected to said electrodes through coaxial cables 7 and 8, and a pair of unique "air switches" 9 and 15. Tuning stubs 11 and 12 are provided for adjusting the individual left and right electrode sets to proper tuning. The upper electrode sets are mounted for vertical reciprocation toward and away from the lower electrode sets; and, in the embodiment illustrated, this is effected by an air cylinder and piston arrangement 13. A work-piece-supporting table 14 and a lower mounting table 15 are positioned upon a framework 16 which is preferably arranged so that a machine operator may sit in front of the machine and feed the workpieces thereto.

The upper electrode assemblies

Each upper electrode assembly (Figure 5) includes a metal strip electrode 17 which is received within a polystyrene facing member 18. The facing member is secured to a backing or supporting member 19 of fabric-reinforced insulating material such as "Micarta." A lead connector 20 is received within a threaded opening in electrode strip 17, passes through supporting member 19 and a bushing 21. A flat metal lead 22 is secured to the connector 20 and to a plate 23, forming part of an associated "air switch." A screw 24 passes through the plate 23 and is received within the supporting member 19, attaching the plate 23 in fixed position with respect to the electrode structure.

40 A crosshead 25 (Figure 3) of electrical insulation material connects the two electrode assemblies 2 and 3 through electrically insulating mounting blocks 26 and 27 and metal mounting brackets 28 and 29. The crosshead 25 is adjustably mounted on a T-shaped head support 30 by screws 31, 32, and 33 which pass through slotted openings in the crosshead 25. The head support 30 is secured to the air cylinder and piston arrangement 13 (Figure 1) which imparts a vertical reciprocatory movement to the electrode assemblies as will be more fully hereinafter described.

45 There is no direct electrical connection, i. e., no mechanical connection, between the electrodes 17 and the high-frequency source and, therefore, no substantial problem of maintaining reliable and consistent circuit completion is encountered.

The lower electrode assemblies

50 Each lower electrode assembly (Figure 6) includes a metal strip electrode 34 which is preferably complementary to the cooperating upper electrode 17 and is also received within a polystyrene facing member 35. A backup 36 of "Teflon" insulation or other material having the requisite dielectric properties for this service is provided for the electrode strip. Below this is positioned a backing or supporting member 37 of "Micarta." A "Micarta" spacing plate 38 is disposed below the member 37 and screws 39 (Figure 3) which pass through members 36 and 37, and bushings 40 are received within tapped openings in spacing plate 38. The spacing plate is in turn supported by a metal connecting plate 41 to which it is secured by screws 42 which pass through bushings 43 and are received within connecting plate

41. The metal connecting plate 41 is disposed above lower mounting table 15 and is secured thereto by screws 44 which pass through bushings 45 and are received within threaded openings in the lower mounting table. An outer shielding tube 46 of the coaxial conductor associated with the electrode assembly is electrically connected to the connecting plate 41 by soldering. The electrode 34 is connected to the high-frequency source through a rod 47 which passes through the shielding tube 46 of the coaxial conductor. The rod 47 is received within a threaded opening provided in the electrode strip 34. The spacing plate 38 serves to stagger the fastenings which connect the members 34-37 and plate 41 and provides a more effective insulation of the high potential electrode strip 34 from ground, the connecting plate 41 being at ground potential and electrode strip 34 at maximum potential above ground.

The "air switches"

Each of the air switches 9 and 10 (Figure 7) is formed of metal plates 48 and 49 which are connected together by screws which pass through plate 48 and bushing 50 and are received within threaded openings in plate 49. The assembly is held in fixed position by soldering the plate 48 to the connecting plate 41. Since plates 48 and 49 are electrically connected to one another and to plate 41 which is in turn electrically connected to shielding tube 46 which constitutes the grounded leg of the high-frequency source, when plate 23 which is electrically connected to the upper electrode 17 is disposed between plates 48 and 49, the electrode 17 is capacitively coupled to the high-frequency source at essentially ground potential. The plates 48 and 49 are of extensive surface area and are spaced as closely together as reasonably possible to receive plate 23 therebetween without actual physical contact. It is desirable to keep the voltage loss to as low a value as possible. Effective capacitive coupling is effected when the upper electrodes have been brought to a position overlying and in tangential contact with a workpiece disposed between the upper and lower electrodes. The capacity of the "air switches" 9 and 10 is substantially greater than the capacity of the load disposed between the electrodes 17 and 34, assuring the development of nearly all available generator voltage in the workpiece under treatment. The stray capacitance between the high potential electrode 34 and the plates of the "air switches" 9 and 10, as well as the other elements of the grounded leg of the system, is so small as to have no substantial effect on the operation of the system. Stated in other words, the impedance of the air switch system is negligible, and essentially all of the generator voltage is applied to the workpiece which constitutes the load.

Suitable guarding may be provided to protect the machine operator from injury by the reciprocating plates 23. In the embodiment illustrated in Figure 3, each of the guards includes an upright panel 52 of insulation material fastened to the lower mounting table 15 by an angle bracket 53. Edge strips 54 and 55 of insulation material and a metal cover plate 56 are fastened to the panel 52 by screws 57. The cover plate 56 is provided with a slotted opening 58 to pass the flat metal lead 22 and fastening 24. A bracket 59 extends from mounting table 15 to the upper portion of panel 52 and serves with angle bracket 53 to hold the guard in proper position.

The coaxial cable and tuning stub arrangement

The coaxial cables 7 and 8 (Figure 1) originate at the oscillator 6 and extend through junction boxes 60-64 and then, as shown in Figure 6, are connected to the lower electrode strips 34 and connecting plates 41. In order to obtain a symmetrical system, the coaxial cable extends to junction box 62 which is disposed midway between the electrode assemblies, entering at the rear

of the box (Figure 2) and then branching out in opposite directions to junction boxes 63 and 64 (Figure 1). A hollow copper tube and brass rod coaxial line as shown in Figures 6 and 7 may be used, but other effective coaxial cable arrangements may be substituted.

The tuning stubs 11 and 12 (Figure 1) serve to balance the right and left electrode sets for equal voltage and also to so adjust the impedance value that the resultant impedance at the oscillator output can be tuned for efficient load matching with a tuning stub 65 which projects from junction box 60. A variable loop coupler may be provided within the oscillator 6 to furnish final coupling adjustment to the output of the oscillator. Such coupling is generally conventional, and the details of the tuning stubs is not of critical importance. They may be simply constructed as shown in section in the lower left-hand portion of Figure 1 where tube 66 of tuning stub 11 is received within junction box 64 and soldered thereto. The tube 66 receives a tuning member 67 which may be in the form of a brass cylinder which fits within the wall of the tube 66 and is movable to adjusted position therein. The tuning member 67 is drilled and tapped throughout its length and is received on a threaded supporting rod 68 which extends throughout the length of the tube 66 and is anchored in the junction box 64 but insulated therefrom, preferably by connection of supporting rod 68 to the rod 47 (Figure 6) of the lower electrode assembly. The tuning member 67 may be adjusted by providing a projection 69 thereon which may be engaged by a hollow adjusting wrench inserted into the tube 66 from the lower end thereof. A cover cap 70 is preferably provided over the end of the tube 66 and may be held in place by a nut 71 threaded onto rod 68. The cover cap 70 is removed when the tuning member 67 is to be adjusted.

The crosshead actuating assembly

The crosshead 25 (Figures 1 and 2) which carries the upper electrode assemblies 2 and 3 is mounted for vertical reciprocation on a rod 72 which is guided in bearings 73 and 74 fixed to the frame of the machine. A guide rod 75 (Figure 2) which is mounted in bearings (not shown) attached to the frame of the machine assures proper alignment of the crosshead 25 in service. The crosshead actuating mechanism includes the air cylinder and piston 13, the piston rod 76 of which is connected to actuating rod 72 of the crosshead by an offset connection 77. The air cylinder 13 is supplied with air from a source S, and the application of air to the air cylinder and piston 13 is controlled in proper timed relationship with the application of the high-frequency field to the workpiece. Any suitable equipment may be provided to control the operation of the air cylinder and piston arrangement 13 and the high-frequency oscillator in proper sequence, and limit switches 78, 79, and 80 which are shown in Figure 1 may form part of the control system. Such systems are conventional and will vary with the type of workpiece to be operated upon, the time interval required for positioning the pieces to be joined, and other variable factors.

The work holder

As mentioned previously a workpiece-supporting table 14 is provided, and where irregularly shaped pieces are to be joined it is desirable to provide a positioning jig. In the embodiment illustrated in Figures 3 and 4, the workpiece is in the form of a cork composition gasket made up of an end piece 81 and two side pieces 82 and 83 to be joined along the lines 84 and 85. A similar end piece will be joined to the side pieces at their opposite ends, which are not shown in the drawing, to complete the gasket.

There is provided a positioning jig which includes a base plate 86 of insulation material which is fastened by screws 87 to supporting table 14. Guides are provided

for positioning the pieces in proper alignment at each joint. Each of these guides comprises a piece of insulation material 88 of dielectric properties adequate to withstand repeated operation within the high-frequency field and the temperature elevation created therein, such as "Teflon" insulation. Each guide piece 88 overlies the electrode strip 34 and the polystyrene facing member 35 and is secured to the base plate 86 and the facing member 35 by screws 89 and 90 which pass through openings in the guide piece 88 and are received within threaded openings in the base plate and facing member. This guide piece 88 projects above the surface of the electrode strip 34 a distance about equal to the thickness of the workpiece being operated upon. A second guide piece 91 similar to guide piece 88 is mounted in spaced relationship thereto on the lower electrode assembly, the spacing being such that the gasket segments may be positioned between the guide pieces and held in such position by frictional engagement therewith. Screws 92 hold the guide piece 91 in position on the facing member 35.

Operation of the machine

In the operation of the device, the oscillator 6 is connected to a source of energizing voltage, and cylinder and piston arrangement 13 is connected to air source S. Gasket segments to be joined have previously been coated on their edges which are to be joined with an adhesive such as a conventional phenolic resin adhesive designed for dielectric curing. The adhesive is preferably applied to a stack of the segments and dried. All edges to be joined are preferably adhesive coated.

The operator inserts an end piece 81 (Figure 3) into the jig where it is frictionally held. The dried adhesive coated edges of the piece 81 will lie about midway longitudinally of the electrode strips 34 which, as noted in Figure 6, are substantially longer than the joint to be made. This provides adequate electrode surface for bonding gaskets of different sizes from strips of different widths. After gasket segment 81 has been positioned, the operator brings the adhesive-coated edges of segments 82 and 83 into abutting relationship with the adhesive-coated edges of segment 81, holding the segments 82 and 83 in his hands and pressing them toward segment 81 to bring the parts into firm engagement. The air cylinder and piston arrangement is then actuated, as by movement of a foot-controlled valve pressed by the operator, and this procedure brings the crosshead and the associated upper electrode assemblies from the position shown in Figure 3 to the position shown in Figure 4 and in more detail in Figure 7. In this position the upper electrode 17 overlies the gasket segments at the adhesive-coated joint, and the pieces are confined at the joint between electrodes 17 and 34 and edge guides 88 and 91 of the positioning jig. No substantial pressure needs to be applied to the segments vertically at the joints, but good contact should be maintained by pressure applied by hand by the operator.

As the crosshead 25 is lowered, the plates 23 of "air switches" 9 and 10 pass between plates 48 and 49 (Figure 7) and thus electrode strip 17 is capacitively coupled to the high-frequency source. Switch 80 (Figure 1) which controls the oscillator is actuated upon lowering of the crosshead, and a high-frequency voltage is applied to the electrodes through the coaxial cables 11 and 12 and the "air switches" 9 and 10. For joining the gasket segments as shown a 200 megacycle, 150 watt, cyclic duty oscillator may be employed. Preferably the electrical control circuit for the system includes a timing mechanism which controls the duration of the heating cycle. For instance, this may provide a cycle of a few seconds when the high-frequency field is applied to the glue lines to activate them, a few seconds dwell time after interruption or discontinuance of the field application for the adhesive to set while the parts are confined, and then an

automatic elevation of the crosshead 25 for the removal of the joined workpiece.

Upon completion of these operations, if an end piece is to be applied to the opposite ends of segments 82 and 83, such end piece will be inserted in the jig in the same manner as end piece 81, the opposite ends of segments 82 and 83 will be brought into abutting relationship with the new end piece, and the operation will be repeated, thus forming a complete gasket.

10 I claim:

1. In a device of the type described, the combination of a fixed electrode, a movable electrode spaced from the fixed electrode, means for moving said movable electrode relative to said fixed electrode from an inoperative position to an operative position embracing a workpiece disposed therebetween and constituting a load to be heated, means directly connecting said fixed electrode to one side of a source of high-frequency alternating electric voltage, and means carried by said movable electrode and effective upon movement from said inoperative to said operative position to closely capacitively couple said electrode to the other side of said high-frequency source with negligible impedance in said coupling, said last named means comprising an air switch the capacity of which is substantially greater than the capacity of the load disposed between said electrodes and including a fixed metal plate connected to said high-frequency source and a metal plate connected to said movable electrode for disposition in effective capacitive coupling relationship with said fixed metal plate upon movement of said movable electrode to said operative position to provide a system in which substantially all available voltage from said high-frequency source will be developed within said workpiece.

2. In a device of the type described, the combination of a fixed electrode, a movable electrode spaced from the fixed electrode, means for moving said movable electrode relative to said fixed electrode from an inoperative position to an operative position embracing a workpiece disposed therebetween, means directly connecting said fixed electrode to one side of a source of high-frequency alternating electric voltage above ground potential, and an air switch for coupling said movable electrode to said high-frequency source comprising a pair of fixed metal plates connected to said high-frequency source at substantially ground potential and a single metal plate connected to said movable electrode for disposition in effective capacitive coupling relationship between said fixed metal plates upon movement of said movable electrode to said operative position to closely couple said movable electrode to said high-frequency source.

3. In a device of the type described, the combination of a pair of fixed electrodes disposed in spaced relationship, a pair of movable electrodes disposed in spaced relationship complementary to said fixed electrodes, means for moving said movable electrodes relative to said fixed electrodes from an inoperative position to an operative position embracing a workpiece disposed between said spaced complementary electrodes, a coaxial cable connecting said pairs of electrodes to a source of high-frequency alternating electric voltage, the shield of said cable being at ground potential and the inner conductor of said cable being at a potential above ground, said conductor being connected to said fixed electrodes and said shield being connected to said movable electrodes by a pair of air switches substantially at ground potential, each switch comprising spaced metal condenser plates movable with respect to one another, means connecting one of said condenser plates to each of said movable electrodes, and means guiding said moving means for said movable electrodes to bring said condenser plates into effective capacitive coupling relationship coincident with movement of said movable electrodes into operative position with respect to said workpiece.

4. In a device of the type described, the combination

of claim 1 in which there are a pair of movable electrodes and a pair of fixed electrodes with a crosshead connecting the movable electrodes and in which said stationary electrodes are connected to said source above ground potential and said movable electrodes are capacitively coupled by two of said air switches to the other side of said source at ground potential.

5. In a device of the type described, the combination of a fixed electrode positioned upon a mounting plate of dielectric material, a movable electrode displaceable with respect to said fixed electrode from an inoperative position to an operative position embracing a workpiece disposed therebetween, a capacitive coupling device for coupling said movable electrode to a source of high-frequency alternating electric voltage at substantially ground potential comprising a fixed metal plate and a movable metal plate electrically connected to said movable electrode, a connector plate electrically connected to said fixed plate and to said high-frequency source, an insulating spacing plate interposed between said connector plate and an insulating backing plate for said fixed electrode, fastening means for said backing plate received within

said spacing plate, fastening means for said spacing plate received within said connecting plate, and means disposed in spaced relationship to said connecting plate connecting said stationary electrode to said source at a potential above ground.
